LAVATORY EQUIPMENT

James H. Cox, Los Angeles, Calif.

Application May 5, 1936, Serial No. 77,964

11 Claims. (Cl. 4—159)

This invention relates to lavatory equipment and, particularly, to a device for use in washing and rinsing the hair. Its special objects are the production of a lavatory bowl for the purpose stated which shall be attractive in appearance, economical in manufacture, simple in installation and convenient in operation.

In the preferred embodiment of the invention, which is shown in the accompanying drawing, means are provided for supplying both cold and hot water, for mixing them to obtain the desired temperature, and for normally discharging the water directly into the bowl. The rim of the bowl is provided with a deep notch to receive the neck of the patient, as I shall herein term the person who is being treated, who sits or reclines with the nape of her neck in the said notch and her head in the bowl. The water is drained from the bowl through a suitable pipe which is provided with a trap for hair which may have become loosened during the washing operation, said trap being accessible from the bowl and readily disassembled to remove the accumulated hair. The cold and hot waters are led into a manifold wherein they are mixed and from which they are discharged into the bowl past a valve which is normally closed but is automatically opened by the flowing water during the washing operation. Also connected with the manifold is a flexible and extensible hose connection having a valve and a spray-head. This hose connection is looped downwardly and is kept taut by a weight in the form of a deeply-grooved sheave which is supported by the hose with the loop thereof within the groove. The sheave is moved upwardly by pulling on, and thus extending, the hose. The sheave is heavy enough to retract the hose as the pull upon the latter is relaxed, and means are provided for arresting the valve and spray-head in position for easy access to the operator. To guide the sheave and to prevent it from turning laterally, a suitably-positioned well is provided, the same being substantially rectangular in transverse cross section with its sides in substantial contact with the ends of the sheave. When the washing operation is complete, the spray-head is moved upwardly and forwardly over the bowl and its controlling valve is opened. That relieves the pressure upon the automatically operating valve hereinbefore mentioned and permits it to close, thus shutting off the flow of the washing water and causing the water to be discharged through the spray-head for rinsing purposes.

The apparatus thus referred to necessarily embodies details of construction which, however,

may be modified without departure from the principles of my invention, and it is desired that it be understood that the appended claims are not intended to be limited to such details any farther than the terms employed therein render necessary.

In the drawing, Fig. 1 is a perspective view of my invention in its preferred form, parts being broken away and other parts shown in section; Fig. 2 is a transverse section through the drain-pipe and hair-trap as on the line 2—2 of Fig. 1; Fig. 3 is a vertical section taken centrally through the hair-trap and associated parts; Fig. 4 is a vertical fore and aft section through the rear parts of the bowl and through the guide, showing the flexible hose-connection for the spray-head; Fig. 5 is a section taken longitudinally and centrally through the spout above the bowl and showing the water-controlled valve therein and Fig. 6 is a transverse section on the line 6—6 of Fig. 4. Figs. 2 to 6 are on an enlarged scale as compared with Fig. 1.

Referring to the drawing, 12 is the lavatory bowl, the same having a marginal flange or rim 13 and an upstanding member 14 at the rear for attachment to a wall or other support. Centrally positioned in front of said member and at the rear of the bowl proper is a rectangularly-shaped protuberance 15 forming a housing, for a purpose to be described. All of these parts are preferably formed of a single, integral casting or stamping which, for sanitation, is preferably coated with enamel; or these parts may be of earthenware suitably glazed.

At one point, preferably in the front, as shown, the rim 13 of the bowl is provided with a deep notch or depression 16 which is adapted to receive the nape of the neck of the patient as she sits or reclines before it with her head in or over the bowl. In its lowest part, the bowl is provided with an aperture which is surrounded by a downwardly-extending flange 17, as best seen in Fig. 3. The aperture and flange are preferably circular in outline. Surrounding the aperture the bowl is preferably beveled, as at 18. Fitted within the aperture and extending for some distance below the bowl, is a drain member 19, the upper end of which is provided with an outwardly-turned flange which rests upon the bevel 18 and forms a water-tight joint therewith. At its lower end, the member 19 is tapered inwardly and is suitably connected with the drain-pipe 20. Within the interior of the member 19 is a pair of nested cup-like members 21 and 22, the same being spaced to provide a cup-shaped chamber 23. Both

of said members are provided with outstanding beveled flanges at their upper edges which rest one upon the other while the flange of the outer member rests upon the flange of the drain member 19. The inner member 22 is provided with a plurality of small perforations 24 in its bottom. The bottom of the outer member 21 is imperforate, but a row of perforations 25 extends about and through its side walls some distance above the bottom of the inner member. The water flowing from the bowl is thus forced to rise within the outer member before it can pass through the perforations 25, and any hair or other matter carried by the water is trapped within the member 22 or within the space 23 between the members. The members are not fixed in position and can be readily lifted out to clear away the hair or other accumulated matter. The structure is, therefore, an effective trap.

Leading from the rear into the housing 15 is a pair of supply pipes for the hot and cold water respectively. One of these pipes, say the hot-water pipe, is shown at 26 in Fig. 1. The other pipe is shown at 27 in Fig. 4. Of course, it is immaterial which is the hot-water pipe. At their forward ends, these pipes are connected with a manifold or mixer 28. The flow of the water through these pipes is controlled by valves the stems of which project through the upper wall 30 of the housing 15 and are provided with suitable hand grips or levers 29 and 30 respectively. The water for the washing operation is discharged from the mixer forwardly through a down-turned spout 31 in front of the housing 35 and above the bowl. In the connections between the mixer and the spout is a valve which is normally closed but is adapted to be opened by the water as it flows toward the spout. Any suitable connections and valve may be employed, that shown comprising a nipple 32 which is threaded into the mixer 28 and projects through the front wall of the housing, the spout being screwed onto the nipple, suitable nuts 33 holding the nipple in place. The forward end of the nipple is provided with a seat for a valve 34 which may be a ball, as shown, or any other suitably shaped valve member which fits upon said seat. That part of the spout which surrounds the valve is bored or cored to receive a helical spring 35 which is compressed between the valve and an internal shoulder 36 within the spout. The spring is relatively weak so that a comparatively slight water-pressure is sufficient to open the valve. The valve itself may be formed of any suitable material.

Connected with the mixer or manifold between the supply pipes 26 and 27 is a flexible pipe 37 which is looped downwardly and is then extended upwardly through an aperture 38 in the upper part of the member 14, the pipe being provided with a ball-like enlargement 39 to hold the pipe in the looped formation shown in Fig. 4. At its upper or outer end the pipe is provided with a spray-head 40, the flow of the water to it being controlled by any suitable hand-operated valve, as indicated at 41.

To hold the flexible pipe taut and to pull it back after it has been extended, as will be more fully explained, I provide a mobile weight in the form of a sheave 42, the same having a deep peripheral groove midway between its ends in which the loop of the pipe reposess. The ends of the sheave are parallel and fit between the side walls of a well or casing 43 so as to be guided by said walls and be prevented from turning lateral-

ly; for if the sheave were permitted so to turn, the vertical portions of the pipe would wrap about each other and prevent or limit the outward movement of the pipe. The deep groove in the sheave holds the pipe centrally positioned in the well 43 and holds it out of contact with the guide walls of the well. The well may be attached to any conveniently-positioned part of the apparatus, as by a bracket 44 which is fastened to the well and the housing 15.

As will be seen in Fig. 1, the rim of the bowl is approximately rectangular in plan, the side edges being substantially perpendicular to the attaching member 14. This provides a flat, horizontal surface, 45, at each side of the housing 15 upon which to place soap, glasses or other articles which may be employed.

The operation may be briefly described as follows: The valves at 29 and 30 having been respectively adjusted until the effluent water at the 20 spout is of the desired temperature the patient sits or reclines in front of the bowl with the nape of her neck in the notch 16 and her head over the bowl. Her hair is then thoroughly washed. During this operation, the valve 41 at 25 the spray-head is closed, and the water opens and passes the valve 34 and flows through the spout 31. Usually, soaps or other toilet preparations which create a lather, are employed so that it is necessary that the hair be thoroughly rinsed. 30 The operator thereupon grasps the spray-head, pulls it upwardly and forwardly to its proper spraying position and opens the valve 41. That relieves the pressure upon the valve 34 and allows it to close, thus diverting all the water to 35 the spray-head. Having thoroughly rinsed the hair, all valves are closed and the sheave-weight is permitted to pull the flexible pipe back into its normal position. Finally, the trap members 21 and 22 may be removed, if need be, cleaned and 40 returned to their normal positions, after which the apparatus is ready for another patient.

As will be noted from Fig. 4, the diameter of the sheave 42 is shorter than the transverse dimension of the guide casing 43. This not only 45 permits the sheave to enter the casing but prevents the jamming of the flexible pipe 37 between the sheave and casing.

If the flexible pipe were drawn out too far it would be bent abruptly at its connection with the 50 manifold or mixer and would be liable to be pulled loose or to start a leak at that point. To prevent that possible result, I prefer to provide a readily removable stop 46 which may be attached to the guide casing to project into the 55 path of the sheave to arrest it before the pipe is thus abruptly bent.

While the invention as described is particularly designed for use in washing and rinsing the hair, it is obvious that, with slight modification, it is 60 adapted for other uses. For example, it may be used as a kitchen sink, or as an attachment for a kitchen sink, wherein dishes are washed and sprayed. In that case, the notch 16 would not be needed or desirable; but otherwise the structure and operation would be substantially as shown and described.

Having thus described my invention, I claim:

1. A device of the character described comprising two separate sources of liquid supply, a mixer 70 for the liquids to which said sources are connected and in which the liquids are mixed, two passages for the mixed liquids leading from the said mixer, a valve in one of said passages adapted to close the passage positively against 75

the flow of liquid therein, a pressure-controlled valve in the other passage, and means for pressing the latter valve toward its seat, said latter valve being forced from its seat by the pressure of the water against it when the valve of the first-mentioned passage is closed and to close upon its seat when the latter valve is opened, whereby the water is diverted into the said first-mentioned passage.

10. 2. A device as set forth in claim 1 in which the passage having the positively-acting valve is provided with a spray head, for the purpose specified.

3. A device as set forth in claim 1 in which the passage having the positively-acting valve is within a flexible pipe and in which a spray-head is secured to the pipe, for the purpose specified.

4. A device of the character described comprising a bowl, a spout through which water is delivered to said bowl, a mixer to which said spout is connected, a pair of supply pipes for water connected with said mixer, a valve for and connected with said spout and adapted to close the passage through the latter, a spring acting upon the last-mentioned valve to urge it toward its seat, the spring being adapted to yield under the pressure of the water within the mixer to permit the said valve to open and the water to flow through said spout, a flexible and looped pipe connected with said mixer, a spray-head attached to the pipe at that end which is remote from the mixer, a valve for controlling the flow of the water through the flexible pipe, a mobile weight supported by the flexible pipe within the loop thereof, and a guiding member for said weight adapted to prevent the flexible pipe from twisting.

5. A device as set forth in claim 4 in which the mobile weight is in the form of a sheave the ends of which are adapted to contact with the said guiding member to prevent the sheave from turning laterally.

6. A device as set forth in claim 4 in which the mobile weight is in the form of a sheave the ends of which are in parallel planes and are adapted to contact with the said guiding member, said sheave having a deep peripheral groove winding

between its ends within which groove the looped part of the flexible pipe is disposed, said groove holding the said pipe centrally of the sheave and out of contact with said guiding member and the said guiding member preventing the sheave from turning laterally.

7. A device as set forth in claim 4 in which the guiding member is an elongated box-like structure with its upper end open to receive the flexible pipe and the mobile weight, the said member being substantially rectangular in transverse cross-section with its sides parallel and positioned to engage the weight from turning transversely.

8. A device as set forth in claim 4 in which the guiding member is provided with a stop to arrest the movement of the mobile weight and prevent the flexible pipe from abrupt bending.

9. A device of the character described comprising a pipe through which liquid is supplied, a hollow member to which said pipe is connected, two passages leading from said member, a looped flexible pipe through which one of said passages extends, said pipe being capable of being projected from and retracted toward said hollow member, means for retracting said flexible pipe, a valve for positively closing the passage through the said flexible pipe against the flow of liquid therein, a pressure-controlled valve in the other passage, and means for yieldingly pressing the latter valve toward its seat, said latter valve being adapted to be forced from its seat by the pressure of the water against it when the first-mentioned valve is closed and to close upon its seat when the latter valve is opened, whereby the water is diverted through the passage within the said flexible pipe.

10. A device as set forth in claim 9 in which the means for retracting the looped flexible pipe is a mobile weight supported by said pipe and within the loop thereof.

11. A device as set forth in claim 9 in which the flexible pipe is provided with a spray head, for the purpose specified.

JAMES H. COX. 45
